MOBILE LADDERS

Robert J. Mihalik, Uniontown, Pa., assignor to Harsco Corporation, New York, N.Y., a corporation of Delaware

Filed Aug. 5, 1965, Ser. No. 477,442
4 Claims. (Cl. 182—15)

The present invention relates to mobile ladders. Known types of such ladders include in general a frame mounted on casters, or the like, and a ladder supported in operative position on and extending upwardly and rearwardly at an angle from a front end portion of the frame. The frame also carries at its front end a pair of spaced legs one being arranged adjacent to each of the two casters which support said front end when the apparatus is being moved from place to place. Means are provided for automatically shifting the frame support from said front end casters to said legs and thus immobilizing the unit when the operator mounts the lowermost step, or equivalent element, of the ladder and for restoring the unit to mobile condition by hand or foot actuated devices. Examples of ladder units of this type are described in U.S. Patent Nos. 2,897,910 and 2,798,652.

A different type of ladder for similar uses is illustrated in my U.S. Patent No. 3,175,641 which discloses a construction wherein a single caster mounted at an end portion of the base is actuated to effectively shift the ladder assembly into and out of mobile condition.

An object of the present invention has been to provide in the single caster type of mobile ladders relatively simple and rugged direct or positive acting means by which a user may readily shift the caster to inoperative condition and thus in effect immobilize the apparatus by mounting the bottom step of the ladder and may restore said caster to operative ladder supporting mobile condition by direct positive operation of an actuating lever. Although shifting of the caster to and from operative position is effected in the use of my above noted previously patented ladder structure, the present invention involves structure whereby the shifting, locking and releasing functions are effected with a substantial reduction in the number of involved parts and wherein said parts operate to produce direct and positive adjustment of the caster from one condition to another. These features present certain advantages as compared to constructions in which such shifts necessarily involve spring actuated triggering elements to effect shifting of the caster, locking it in operative position and releasing it in inoperative position.

In general, the present invention may be embodied in a mobile ladder assembly which includes a base having at its front end laterally spaced supporting legs and, at its rear end, laterally spaced supporting casters. A mounting step positioned at the front end of the base also provides in effect the actuating arm of a bell crank fulcrumed in the base and having a latch arm which extends downwardly from the front end of said actuating arm, said bell crank being biased in a counter clockwise direction. A catch lever is pivoted at its rear end on said base and arranged with its front end extending outwardly between said supporting legs; and a swivelling caster is mounted in depending relation on said catch lever. A catch bar is carried on said catch lever in position to be in continuous yielding engagement with said latch arm of the bellcrank. Said latch arm includes a hook portion having a detent notch and a lip extending rearwardly beyond the open end of said notch which is arranged and adapted to operatively engage said catch bar and thereby releasably lock said caster in operative condition to mobilize the base when downward pressure is applied against the outer end of said catch lever; and said latch arm is disengaged from said catch bar when downward

2

pressure is exerted on the step portion of said bellcrank thereby releasing the caster unit from load supporting position and shifting the load to said supporting legs.

Other objects and distinctive features of the present invention not above referred to will appear from the following specification and claims and from the accompanying drawings wherein is shown a preferred embodiment thereof as described in said specification. The showing so made is not intended to be either exhaustive or as limiting the scope of the subject invention. The purpose here is to illustrate the invention so that others skilled in the art may so fully understand it, its principles and applications, that they may embody it and adapt it in any of various forms appropriate to the attainment of any particular or appropriate purpose in use.

In said drawings:

FIG. 1 is a side and FIG. 2 a front elevation showing the base and parts of the superstructure of a mobile ladder assembly embodying the present invention;

FIG. 3, a fragmentary view partly in horizontal section from the line 3—3 of FIG. 2 showing on enlarged scale the location of the caster actuating and locking mechanism in relation to the mounting step which forms a part thereof and in relation to the front legs of the base;

FIG. 4, a fragmentary view in longitudinal vertical section from the line 4—4 of FIG. 3 and showing the caster unit releasably locked in position to support the base in mobile condition;

FIG. 5, a similar view but showing the caster in inoperative position and the leg ends resting securely on the floor to retain the base in immobile condition;

FIG. 6, a transverse vertical section from the line 6—6 of FIG. 4; and

FIG. 7 is a transverse vertical section from the line 7—7 of FIG. 5.

Referring to the drawings, one form of mobile ladder assembly in which my invention may advantageously be embodied includes a base or main frame, indicated generally at 10, on which is mounted a ladder 11 extending upwardly at an appropriate angle from the front end of base 10. The rear end of said base is conveniently supported on casters 12, one at each rear corner. The front end of said base is provided with legs 13 which, when in down or operative position, FIGS. 5 and 7, support the front end of base 10 and maintain said base in immobile condition. And means are provided including a caster 14 whereby said legs may be raised from said down position and, at the same time, move caster 14 into and releasably lock it in supporting position, as seen in FIGS. 4 and 6, thereby bringing the apparatus into mobile condition.

A desirably simple and rugged construction for the above indicated purposes includes essentially two interacting lever systems and appropriate locking and releasing elements mounted generally at the front end of base 10.

One of said lever systems includes a lever arm in the form of a step 15 pivotally mounted adjacent to its front edge on a transverse rod 16 supported at its ends by means to be described, at the front end of base 10, said step 15 being advantageously arranged and adapted to provide in effect the bottom step of the ladder.

Frame 10 includes rear uprights 17, FIG. 1, connected to front legs 13 by horizontal longitudinal braces 18; and said longitudinal braces are connected by horizontal transverse braces 19, FIG. 3. A sub frame adapted to receive step 15, includes a transverse front bar 20, FIG. 3, a transverse rear angle 21, longitudinal side angles 22, 22 connecting said front bar 20 and said rear angle 21, and short upright angles 23 interposed between rear angle 21 and transverse brace 19.

As seen more clearly in FIGS. 3 and 4, the ends of pivot rod 16 are supported in opposed holes in the upright

flanges of side angles 22 so that step 15 rocks in the space defined by bar 20, channel 21 and said angles 22. Springs 24 are interposed between rear portions of step 15 and angle 21, thus normally biasing the rear edge of said step 15 toward normal, or up, position, FIG. 4.

Referring to FIGS. 3 and 4, step 15 includes a cross brace bar 25 and plates 26 secured thereto in transversely spaced relation, as by welding, at their inner ends and each having a hole adjacent to its outer end by which it rotatably engages pivot rod 16. The arrangement is such that plates 26 rock with step 15. A latch arm 27 is secured at one end, as by welding, to an outer end portion of each of plates 26. Each said latch arm extends downwardly from the step and is provided at its bottom or free end with a hook-like terminal wherein a recess 28 opening through the inner face of said arm 27 is defined in part by a lip 29 extending inwardly beyond said inner face of arm 27 and the open end of recess 28.

The parts above described including step 15, plates 26 and latch arms 27 constitute in function a lever system or bell crank fulcrumed on rod 16 and arranged and adapted to cooperate with another lever system in a manner to control the position of caster 14 and connected parts and thereby to readily adjust the apparatus between mobile and immobile conditions.

As seen in FIGS. 3 and 4, said other lever system includes a foot actuated lever, or treadle, conveniently in the form of a yoke shaped lever 30 comprising an outer rounded end and parallel inwardly extending arms 31. A plate 32 welded to portions of the bottom surfaces of arms 31 provides a base on the bottom face of which the caster assembly is mounted to swivel freely.

A hinge tube 33 is welded to an under side surface of angle 21 and supports the inner ends of said arms 31 of the treadle lever 30. For this purpose, each of said inner ends has a tubular collar 34, FIG. 6, of the same internal diameter as that of the hinge tube 33. A hinge pin conveniently in the form of a tube 35 extends through said hinge tube 33 and said collars 34 where it is retained by suitable means such as a washer 36 at one end and a cotter pin 37 at the opposite end (left FIGS. 6 and 7).

It is noted that the step lever system (step 15, arm or latch 27) is fulcrumed (rod 16) near the front edge of the step frame; whereas the treadle lever system (30, 31) is fulcrumed or hinged on pin 35 near the rear edge of said step frame and at a level below that of the step fulcrum rod 16. Also, the distance from the hinge axis to the floor contacting line of caster 14, FIG. 4, is greater than the vertical distance from said hinge axis to the floor level, FIG. 5. Accordingly, by moving caster 14 from FIG. 5 position to FIG. 4 position, the front end of the base or main frame is lifted thereby raising the bottom ends of legs 13 off the floor, FIG. 6, to an extent determined by the difference between said distance from the hinge axis to the floor contacting line of caster 14 and the vertical distance from said axis to the floor level. This difference is approximately the vertical distance between the floor level and the bottom end of leg 13, FIG. 4.

An embodiment of the present invention also includes means operatively interposed between step 15 and lever arms 31 whereby caster 14 carried by said arms is automatically and releasably locked in operative position, FIG. 4, when the outer end of treadle 30 is swung on hinge pin 35 downwardly into said FIG. 4 position, as by foot pressure applied by an operator. For this purpose, a catch bar 38, FIG. 3, is secured in position to cooperate with latches 27 as by welding to upwardly exposed surface portions of the parallel arms 31.

Free end portions or extensions 39 of bar 38 shown as deflected from the longitudinal axis thereof at a slight angle, are arranged to operatively engage inwardly directed edge faces of said latches 27 including those of the recesses 28.

In the extreme end position of catch bar 38, FIG. 4, 75

its end portions are engaged in said recesses 28. However, when an operator mounts on step 15, his weight applied against spring 24 rocks the latch arms 27 in a clockwise direction and to such an extent as to disengage recess 28 from ends 39 of catch bar 38. As said ends 39 are thus released from locking relation to recess 28, legs 13 drop by gravity into operative base supporting position (immobile condition), as seen in FIGS. 5 and 7; and caster 14 is free to move out of base supporting position. The change from mobile (FIG. 4) condition to immobile (FIG. 5) condition obtains as soon as latch 27 disengages recesses 28 from the end portions 39 of catch bar 38. In this condition of the parts, caster 14 may remain in contact with the floor without, however, bearing any weight other than its own and that of arms 31 and catch bar 38; or conditions of use may be such that arms 31 of the treadle are vigorously deflected to the extreme position shown in FIG. 5 with the end portions 39 of catch bar resting against upper end portions of the inwardly exposed faces and lightly clamped against under edge portions of plates 26. It is noted that when the outer end of the treadle is swung down from FIG. 5 toward FIG. 4 position, said outer ends 39 of catch bar 38 may ride along inner edge face portions of latch arm 27 until they are stopped by lip 29 at which point biasing action of springs 24 brings the recesses 28 of said latch arms 27 into locking engagement with said ends 39.

From the foregoing description and stated mode of operation, it appears that apparatus embodying the present invention provides the safety feature that, when an operator mounts the bottom step, the caster 14 is automatically displaced from down or operative mobile position and the legs move down to support the front end of the base and in effect automatically lock the apparatus against rolling movement. The base is rendered mobile by downward pressure of the operator's foot on the free end of the catch lever, or treadle.

These advantages are in addition to simplified economical structure and to direct and positive operation of the locking parts. Thus, no springs or equivalent are employed to move the caster into operative position or to retract it therefrom.

The operator's weight on the mounting step releases the lock and the front legs drop by gravity into supporting position, FIG. 5.

In this operation, when the user's weight causes latch arm 27 to swing clockwise and thus to disengage notch 28 from catch bar 39, the free end of the treadle or catch lever 39 swings clockwise and catch bar 39 rides upwardly along latch arm 27. Ordinarily, the application of releasing pressure on the step is momentary so that springs 24 are compressed only for a correspondingly short time. When this pressure is released, as when the operator's weight is removed from step 15, springs 24 bias latch arm 27 counterclockwise so that the inner edge face of said latch arm now bears yieldingly against catch bar 38, in effect tending to cam it upwardly toward its end position as seen in FIG. 5. Inasmuch as the catch bar, catch lever and caster are relatively light in weight, the pressure exerted on catch bar 38 by operation of springs 24 is sufficient to retain said parts in their FIG. 5 positions. However, even if, through slackening of said springs, or otherwise, catch bar 38 should slide down toward notch 28, it cannot engage therewith without pressure positively applied to the outer end portion of latch lever 30; and caster 14 remains inoperative until it is forced down into its FIG. 4 position.

I claim:

1. In a mobile ladder assembly the combination which includes a base having at its front end laterally spaced supporting legs and at its rear end laterally spaced supporting casters, a mounting step constituting the actuating arm of a bellcrank fulcrumed at the front end of said base and normally biased counter-clockwise, said actuating arm having a latch arm extending downwardly

from front end portions thereof, a catch lever pivoted at its rear end to said base and positioned with its front end extending forwardly between said front legs, a swivel caster mounted on and depending from an intermediate portion of said catch lever, a catch bar transversely arranged on said catch lever in operative relation to said latch arm, said latch arm including a hook portion arranged and adapted to be operatively engaged with and to be disengaged from said catch bar whereby, when the rear end portion of the actuating arm of the bellcrank is deflected downwardly by pressure applied on rear portions of said step, said latch arm is actuated clockwise to disengage said hook portion thereof from said catch bar and thus free the front end of said catch lever to rock clockwise into inoperative position thereby to release said legs into base supporting condition and, when the front end of said catch lever is pressed downwardly from said inoperative position, said catch bar is returned to operative hook engaging position, thereby to move said caster to and retain the same in operative position to support the front end of said base in mobile condition and to retain said legs in raised non-supporting position.

2. In a mobile ladder assembly wherein a ladder is operatively mounted on a mobile base which has supporting legs at one end and a caster operatively arranged between said legs and means are provided whereby said end of the base can readily be adjusted at will to rest on said legs or to rest on said caster, the combination in which said adjusting means include a catch lever pivotally mounted on said base and operatively connected to the caster to move the same and thereby lift said legs off a supporting surface while employing the caster as a ful-

crum, and a bellcrank operatively mounted to rock on said base and operatively connected to said catch lever and arranged and adapted to release the caster from said surface engaging position and thereby permit the legs to move to operatively engage said supporting surface, said bellcrank including an actuating arm arranged and adapted to serve as a step for mounting said base and having a latch arm extending downwardly from said actuating arm and positioned and adapted to be operatively engaged with and disengaged from said catch lever.

5 3. A mobile ladder assembly as defined in claim 2 and wherein said lever includes a catch bar and said latch arm of the bellcrank includes a detent notch which is engageable with said catch bar to lock the base in mobile condition and is disengageable from said catch bar to bring said base into immobile condition.

10 15 4. A mobile ladder assembly as defined in claim 3 and wherein said bellcrank is biased in a direction to retain said latch arm in yielding engagement with said catch bar.
